RUNPROOF FABRIC AND METHOD OF
MAKING SAMEGustav Gastrich, Wyomissing, Pa., assignor, by
mesne assignments, to Berkshire Knitting Mills,
Wyomissing, Pa., a corporation of Pennsylvania

Application May 7, 1932, Serial No. 609,837

19 Claims. (Cl. 66—198)

This invention relates to knitted fabrics and particularly to methods of making run-proof fabrics and to mechanism for automatically making such fabrics on full fashioned knitting machines.

Although it has heretofore been proposed to make run-proof fabrics by interlocking certain loops of a course with adjacent loops, alternating the interlocking in succeeding courses, it has not been possible to effect such interlocking of loops in a fully automatic operation of a full-fashioned knitting machine.

An object of this invention is to interlock, in any one of a variety of ways, certain loops of a course with adjacent loops and to effect the interlocking in succeeding courses in such manner that if the thread breaks the unravelling thereof cannot take place beyond the next succeeding interlocked loop.

Another object of this invention is to provide fully automatic mechanism for effecting such interlocking on a straight bar knitting machine.

Other objects and advantages of this invention will be apparent upon consideration of the following description and appended claims when read in conjunction with the accompanying drawings.

In carrying out this invention I first form plain loops and then before the loops are cast off the needles I spread certain loops over adjacent needles by means of transfer points and effect the engagement of the spread loops with said needles by a timed cooperation of the needles and transfer points so that the spread loops become interengaged or interlocked with the loops on said needles.

In making certain forms of fabric according to this invention, I spread the loops which it is desired to interlock over two adjacent needles while in other forms of runproof fabric I spread the loops over a single adjacent needle. The interlocked loops may be each loop, alternated loops, or only loops at certain intervals, in a course, "skipping" the intervening non-locked loops. Loops may also be interlocked in every course or only in certain spaced courses between which are courses of plain loops.

In succeeding interlocking courses the system of interlocking is varied so that interlocked loops occur in every wale of the fabric. The spreading of loops for interlocking in succeeding interlocking courses may be in the same or in the opposite direction to the spreading of loops in previous courses.

In the drawings:

Figure 1 is an enlarged view of a piece of fabric having determinedly spaced loops in each course interlocked with adjacent loops in accordance with the invention, the spreading and interlocking of loops proceeding progressively in successive courses; 5

Figure 2 is an enlarged view of a piece of fabric having alternate loops in each course spread over two adjacent loops and interlocked, alternate loops being interlocked in successive courses. 10

Figure 3 is an enlarged view of a piece of fabric having alternate loops in each course spread over a single adjacent loop and interlocking, alternate loops being interlocked and the loops being spread in opposite directions in successive courses. 15

Figure 4 is a vertical sectional view of a portion of a full fashioned knitting machine embodying mechanism for effecting the spreading and interlocking of loops in accordance with the invention. 20

Figures 5a, 5b, 5c and 5d are diagrammatic views illustrating a series of primary steps for effecting loop interlocking in accordance with the invention. 25

Figures 6e, 6f, 6g, and 6h are perspective views of conventional knitting machine elements and illustrate a series of secondary steps for interlocking loops according to one manner of practicing the invention; 30

Figures 7e, 7f, 7g and 7h illustrate another series of secondary steps for interlocking loops in another manner; and

Figure 8 is an enlarged view of a piece of fabric showing another type of loop formation. 35

The words "primary" and "secondary" used immediately above have no meaning other than that the series of steps illustrated in Figures 6e to h and Figs. 7e to h, respectively, each follow the series of steps illustrated in Figures 5a to d for effecting loop interlocking in two different ways. There are no figures designated 7a to d nor 6a to d, the designations given being chosen to facilitate following the sequence of operations as described herein. 40

In the drawings the letters A, B, C, D are employed to designate successive courses and the characters 4A, 5A, 6A; 4B, 5B, 6B and 4C, 5C and 6C designate adjacent loops in the corresponding courses while the numerals 4, 5, 6 etc. when employed alone designate the needles corresponding to the loops. Inasmuch as the manner of interlocking the various loops of a course is identical the following description will, for sim- 45 50 55

plicity, deal in detail only with the spreading and interlocking of a single loop in a course.

The mechanism for making the novel run-proof fabrics is shown in Figure 4, in which the numeral

- 5 10 designates the usual needle bar provided with a plurality of needles 4, 5, 6 etc. and operable for vertical movements by a cam 12 on cam shaft 13 through levers 14 and 15 the latter of which has a roller 16 engageable with cam 12 when shaft 10 13 is shifted axially in well known manner for narrowing or lace work.

The horizontal movements of the needles are controlled by a cam 17 acting through presser levers 18 on the needle bar.

- 15 20 The usual front narrowing shaft 20 is vertically movable about rear narrowing shaft 21 to dip the usual narrowing points into needle cooperation and also carries a transfer point rod 22 provided with transfer points 23. Cam shaft 13 has a 20 cam 24 operative on arm 25 and rod 26, when the shaft is shifted axially, for dipping the narrowing shaft 20 and transfer rod 22, ordinarily two dips for each cam shaft rotation.

25 The shifting of the transfer points 23 for spreading loops as hereinafter described may be readily effected by any known loop transfer device, the drawings indicating a cam 27 on the cam shaft 13 acting through lever 28, rod 30 and toggle levers 31, 32 on a transfer point shifting device 33 under the control of a pattern chain 34 as more fully described in the copending application of Emil Richter and Paul Schmidt, Ser. No. 561,536 filed Sept. 8, 1931.

30 However, in adapting the mechanism described in said copending application to produce the various interlocked-loop fabrics described hereinafter, the contours of the cams 12 and 24 are designed and the cams are relatively arranged on cam shaft 13 to cause the sequence of transfer 35 point and needle movements illustrated diagrammatically in the figures bearing the major designations 5 to 7.

35 As may be seen from the following description cams 12 and 24 are cooperatively arranged on shaft 13 to assure that the needles 4 etc. remain overlapped with the alined points 23 during the rise of the latter after engaging loops on certain needles in order that the loops may also be retained on the related needles. This assures 40 that in the lateral movement of the points to spread the loops the latter will remain engaged by needles on which they were formed while at the same time becoming engaged with adjacent needles for interlocking purposes as later described.

45 Referring now to Figure 2, Figs. 5a to d and Figs. 6e to h, after thread has been laid, loops have been formed by the sinkers and dividers, and stitches have been drawn through the previous course A (Fig. 2) by the needles as usual, the transfer points descend into registry with alternate needles of the course (Fig. 5a). The needles are then moved against the points and the beards of these alternate needles are thus closed (Fig. 5b). The needles and points then descend below the knock-over bits in unison so that alternate loops become engaged around the points as well as the needles (Fig. 5c). Then instead of the points rising and merely taking the loops off the 50 needles for transfer to other needles, as in ordinary narrowing or lace work operations, the points and needles both rise with the latter moving upwardly more rapidly than the points so that the beards of the needles pass through and 55 are positioned above the loops. The loops are

thus retained on the needles as well as the transfer points and the needles move away from the points, (Fig. 5d) to permit lateral shifting of the latter.

5 While the points and needles remain thus overlapped the points are shifted two needle spaces to the right, or left, so that the loops, as 2B, 4B, engaged by the points are spread or carried across the intermediate needles to positions in front of the second needles from the ones with which the points initially registered, Fig. 6e. After this shifting of the points, the needles and points descend below the knockover bits and the portion *a* of the spread loop 4B is engaged by the beard of the intermediate needle 5 while the portion *b* is retained by the beard of the needle 4 around which the loop was originally formed, Fig. 6f. Although the beard of needle 6 is also open it does not engage the loop portion *a* which is held away therefrom by the transfer point 23. 20 As this action takes place the portion *b* of the spread loop forms twisted or rolled bights *c* and *d* as a result of rolling over the tip of the intermediate needle 5 as the needles descend below the knockover bits, see Fig. 6g. The needles then 25 move against the alined points closing their beards and are then raised, the beard of the needle 6 passing through the twisted loop bight *d* on the engaged point (Fig. 6h) so that the spread loop becomes engaged around the needle 6 as well 30 as the needle 4 on which the loop was formed and the intermediate needle 5 over which the loop portion *b* rolled. The needles are then raised further to position for the laying of the carrier thread for the next course and the points are also 35 raised to inactive position.

When the next course is knit the loops 4C, 5C, and 6C are drawn through various parts of the spread loop 4B, the loop 4C being drawn in normal manner through the spread loop, the loop 5C 40 being drawn through the intermediate loop 5B between the twisted bight *c* formed by portions *a* and *b* of the spread loop 4B and the loop 6C being drawn through the loop 6B in normal manner and also through the twisted bight *d* of the spread 45 loop 4B, the twisted bights thus providing locks for the loops.

The interlocked loop fabric shown in Fig. 8 may be produced by following the steps illustrated in Figs. 5a to 5d and then varying the cooperative 50 relation of the needles and points as shown in Figures 7e to 7h. Fig. 7e shows the spreading of the loops over two adjacent needles. Thereafter, during the descent of the needles with their beards open they are moved slightly closer to the points, without closing the beards however, to position the beard of needle 6 so that needle 6 also engages the portion *a* of the spread loop 4B while as before the intermediate needle 5 engages the portion *a* and the needle 4 engages the portion *b*. 60 (Fig. 7f.) The transfer points 23 do not descend below the knock over bits with the needles and as a result the spread loop 4B is drawn off the point alined with needle 6. In the descent of the needles below the knock over bits the portion *b* of spread loop 4B rolls over the intermediate needle 5 and second needle 6 forming a twisted bight *c* over these needles, the portion *a* being held by both needles 5 and 6 (Fig. 7g).

65 As the needles rise, needles 5 and 6 retain the 70 bight *c* so that a single twisted bight around needles 5 and 6 remains in the spread loop 4B (Fig. 7h). On formation of the next course C the loops 4C, 5C and 6C engage portions of the spread loop, the loop 4C being drawn in normal 75

manner through the spread loop 4B, and loops 5C and 6C being drawn respectively through loops 5B and 6B as usual and also through the twisted bight c formed by the portions a and b of spread 5 loop 4B.

After loops have been spread and interlocked either as shown in Figs. 2, 6e to 6h or in Figs. 7e to 7h, and 8 the loops of succeeding courses may also be spread and interlocked. The spreading 10 and interlocking of loops as described above may be effected in successive courses or with one or more plain courses between the spread and interlocked courses.

Alternate loops in a succeeding course, such as 15 C (Fig. 2), are spread and interlocked as described above for the course B, except that the loops 5D, 7D etc. which correspond to the intermediate or skipped loops 5B, 7B in the previous course (B) are now spread, thus insuring that spread and 20 interlocked loops occur in each wale. To provide for thus spreading these loops, the transfer points may be shifted idly one needle space at the termination of spreading for the previous course (B) or before the spreading shift in the following 25 course C, or D if a plain course intervenes.

The spreading of loops 5C, 7C in the succeeding course may be either in the same or opposite direction to the spreading of loops 4B, 6B in course 30 B as shown in Figs. 2 and 8, respectively.

The modified form of fabric shown in Figure 3 may be produced by spreading alternate loops a single needle, instead of two needles as in Figure 35 7e, and following the steps of Figs. 7f to 7h so that the portions a of the spread loops are engaged by the adjacent needle, as 5. It will be noted that here also the spread loops interlock with adjacent loops, the spread loops in Fig. 3 having twisted bights c interlocking with adjacent loops.

If desired, a fabric in which each loop in each 40 course is interlocked with the adjacent loops, may be made by providing a transfer point for each needle and shifting the loops a single needle space so that the spread loops are engaged around two adjacent needles to interlock each loop with that adjacent. In this case also the spreading of loops 45 may be alternated in direction in successive courses so as to provide interlocks in all wales.

By spreading and interlocking only certain loops at predetermined intervals and skipping the 50 intervening loops in certain courses, rather than spreading and interlocking all or alternate loops in a course, many interlocking variations may be effected with resulting production of quite different appearing fabrics although each fabric 55 may embody spread and interlocked loops of the same type.

For example, Figure 1 illustrates a preferred variation in which every 5th loop is spread and interlocked with skipping of the intervening 4 60 loops and the loops are spread in the same direction and interlocked progressively in a number of successive interlocking courses and then corresponding loops at equal intervals in a number of following interlocking courses are spread in 65 the opposite direction with the spreading and interlocking of loops progressing reversely. That is, in course C of Fig. 1 the 4th, 9th etc. loops are spread to the left and interlocked, in course D the 3rd, 8th, 13th etc. loops are spread to the left and interlocked and so on until course 70 I in which the 3rd, 8th etc. loops are spread to the right, and interlocked and the spreading is to the right for reversely progressive loops, until loops 8, 13, etc. are again reached 75 whereupon the described sequence is re-

peated. In this form of fabric although each course has only a few interlocking loops the progressive spreading and interlocking in successive courses assures that interlocking loops occur at short intervals in each wale so that a broken 5 thread may unravel through only a limited number of courses before it is caught by an interlocked loop and stopped.

The particular interlocking loops employed in Fig. 1 are produced by following the steps illustrated in Figs. 5a to d and 6e to h but spreading the loops 4, 9 etc., 3, 8 etc. or 3, 8 etc., 4, 9 etc.) over only a single adjacent needle. It will be seen that inasmuch as there is no intermediate needle to grasp the loop portion a and since the 15 loop is held by the point 23 away from the needle in front of which the loop is spread, there is no twisted bight c formed as in Fig. 3. However, interlocking is effected by the engagement of an unrolled laterally displaced bight e in each spread 20 loop with the adjacent needle as the latter engages the point 23 and passes up through the spread loop as in Fig. 6g.

It is also to be understood that any of the interlocking loop types shown in Figs. 2, 3 and 8 25 could be also used when following the interlocking system illustrated in Fig. 1.

Referring again to the mechanism illustrated in Fig. 4; it will be seen that the contour of the cam 24 controlling the transfer points is different 30 for forming the interlocked loops of Figs. 7e to h from that employed when forming the interlocked loops of Figs. 6e to h inasmuch as in the latter case the needles and points twice descend together below the knockover bits (Figs. 5c and 6g) while 35 in the former case the needles make the second descent unaccompanied by the points (Fig. 7g). The contour of the usual cam 47 for controlling the horizontal movement of the needles through the presser levers 18 is also slightly different in 40 the two cases, primarily in providing for the movement of the needles toward the points for permitting the needles (as 6) to which loops are spread to engage the loop portion a with their beards. (Fig. 7f.)

For brevity in the specification and claims, the term "run-proof fabric" is used in a generic sense and includes a fabric having one or more interlocking or barrier courses and in which a run will not take place, or in which a run is limited, 50 dependent upon the specific arrangement of barrier courses and locking loops employed; and the term "spread" as applied to loops refers to a loop that extends from the needle creating the loop to another needle in the row of needles in counter 55 distinction to a transferred type of loop which is transferred bodily from the needle creating the loop and positioned bodily upon an adjacent needle.

Although certain types of non-run fabrics are 60 illustrated and described in detail it is to be understood that these are considered as illustrative only, since many variations may be made without departing from the principles of the invention.

What I claim is:

1. The method of making a fabric having run-proof stitches which comprises spreading a needle-engaged loop of a determined course by lateral movement of a lace point extending into said loop, forming a twisted bight in said loop projection, 70 and engaging said bight with a needle holding an adjacent loop in said course to be interlocked with said adjacent loop by the corresponding loop of the following course.

2. The method of making a run proof fabric 75

- which comprises spreading certain loops of determined courses over a plurality of adjacent loops alternately in succeeding courses and forming one bight in each spread loop for interlocking it with one adjacent loop and a second bight for interlocking it with a following adjacent loop.
3. The method of making a run-proof fabric which comprises spreading alternate loops in predetermined courses over a pair of adjacent loops, skipping the intermediate loops; and forming one bight in each spread loop for interlocking it with the intermediate loop and a second closed bight interlocked with the succeeding spread loop.
4. A knitted fabric having non-run stitches, certain of the latter in determined courses extending laterally and being formed with spread loops having rolled or twisted bights at their ends interlocked with loops in adjacent wales.
5. A non-run fabric having a plurality of contiguous interlocking courses each comprising a plurality of pairs of loops, one loop of each pair in a determined course being spread in one direction to provide a bight interlocked with the other loop of said pair, and a loop of a following interlocking course in line with said other loop of each pair being spread in the opposite direction to provide a bight interlocked with a loop in said following course corresponding to the first mentioned loop of each pair.
6. A non-run fabric having a plurality of contiguous interlocking courses each comprising a plurality of pairs of contiguous loops, one loop of each pair in a determined course being spread in one direction and interlocked with the other loop of said pair, and a loop in a following interlocking course in line with said other loop of each pair being spread in the opposite direction and interlocked with the adjacent loop corresponding to said one loop of each pair.
7. A non-run fabric having a plurality of interlocking courses each comprising a plurality of spread loops having laterally displaced twisted bights interlocked with loops not contiguous thereto coursewise of the fabric.
8. A knitted fabric comprising needle loops some of which are twisted and inverted and form yarn holding loops in at least two needle wales and in the same course.
9. A method of knitting with a plurality of spring bearded needles which comprises forming a course of loops, spreading certain of said loops laterally to lie beneath the beards of adjacent needles, retaining the loops upon the needles on which they were formed while drawing the said adjacent needles down with the beards open, whereby the beards of said adjacent needles enter said loops, and causing said loops to be knocked over upon the stems of said adjacent needles with the loops already thereon.
10. The method of knitting in a run-proof fabric comprising forming successive courses, spreading certain loops of a determined course over a plurality of adjacent loops, spreading certain loops of the next adjacent course in staggered relation to the spread loops of said determined course, and simultaneously forming a closed twisted bight in each of said spread loops for interlocking it with said adjacent loop.
11. The method of knitting in a run-proof fabric comprising forming successive courses, spreading determined loops of a course each over the next adjacent loop, and simultaneously forming a twisted bight in each spread loop whereby to interlock the same with the adjacent loop associated therewith.
12. The method of knitting in a run-proof fabric which comprises forming successive courses, spreading selected loops each from one wale into an adjacent wale simultaneously with the knitting of a course, and rolling said spread loops during the spreading operation to produce a twist in said spread loops.
13. A knitted fabric comprising loops some of which form closed loops in their own wales and are spread laterally, twisted, and knit into wales other than those in which they were formed.
14. A knitted fabric comprising loops some of which have yarn receiving loop portions and portions twisted upside-down and knit into wales adjacent to their own, said portions retaining at least three sinker loops in the same course of the fabric.
15. A knitted fabric comprising loops arranged in wales and courses, some of which loops have yarn receiving loop portions and portions twisted upside-down and knit into adjacent wales, said portions retaining at least three sinker loops in the same course of the fabric, and said twisted loops being formed in all wales at suitable intervals and in staggered relationship in different wales to prevent runs in the fabric.
16. A knitted fabric comprising needle and sinker loops, some of which needle loops are twisted and inverted, and knit into at least two wales and hold at least three sinker loops in the same course.
17. A method of knitting a runproof fabric which comprises forming loops between sinkers and needle shanks, spreading portions of certain of the needle loops in certain of the courses on to the beards of needles carrying other loops and transferring said spread portions from the beards to the shanks of the needles while retaining these needle loops upon the needles upon which they were formed.
18. A method of knitting a runproof fabric which comprises forming loops around the shanks of a plurality of spring-beard needles, receiving certain of the needle loops upon transfer points, extending such loops on said points in a course-wise direction, lowering the needles to insert the beards of certain of the needles into said extended loops and reversing said loops by transferring them from the beards to the stems of the needles while retaining the said needle loops upon the needles on which they were formed, and drawing a new course through the loops thus formed.
19. In a method of knitting a run-proof fabric by forming a course of needle and sinker loops with the latter looped through the sinker loops of the preceding course, the method of forming a lock stitch which comprises inserting a transfer member between a needle and the loop thereon, bringing said member into alignment with an adjacent needle to spread a portion of said loop while the main portion of the loop remains upon its needle, introducing into the spread portion of the loop the beard of the needle in alignment therewith, withdrawing the said member from the said spread portion, transferring the latter from the beard to the shank of the needle to superpose said spread portion upon the loop already on the needle, and forming a succeeding course with a needle loop drawn through the said main loop portion and with an adjacent needle loop drawn through both the said spread loop portion and the loop upon which it is superposed.
